Primary Examiner—C. A. Murphy*Attorney, Agent, or Firm*—James Richard Vance[57] **CLAIM**

The ornamental design for a spectacle frame holder, as shown and described.

DESCRIPTION

FIG. 1 is a front perspective view of a spectacle frame holder showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and,
FIG. 7 is a bottom plan view thereof.

The broken lines partially showing a spectacle frame in FIGS. 2 and 3 are for illustrative purposes only and form no part of the claimed design.

FIG. 1

FIG. 4

FIG. 2

FIG. 3

FIG. 5

FIG. 6
